[57] CLAIM

The ornamental design for a goblet retainer insert for a serving tray, as shown.

DESCRIPTION

FIG. 1 is a top plan view of a goblet retainer insert for a serving tray showing my new design;

FIG. 2 is a right side elevational view thereof, the left side being a mirror image thereof;

FIG. 3 is a front elevational view thereof;

FIG. 4 is a rear elevational view thereof; and

FIG. 5 is a bottom plan view thereof.

FIG. 1

FIG. 3

FIG. 2

FIG. 4
